FIG. 5

CONTROL WITH PUSH BUTTON RADIALLY MOUNTED IN DIAL

BACKGROUND OF THE INVENTION

1. Field of the Invention

The invention relates to control apparatus, and in particular, to apparatus having a rotatable control and depressible control; for example, a fluid control apparatus having a rotatable manual valve and a depressible safety valve.

2. Description of the Prior Art

Many apparatus having rotatable controls and depressible controls are contained in the prior art as exemplified by U.S. Pat. Nos. 2,395,470, 2,869,566 and 3,566,117. One prior art fluid control apparatus utilizes a manual valve knob and a separate safety valve reset button interlocked with the manual knob to prevent operation of the reset button unless the manual knob is in a predetermined or "pilot" position; however, the reset button can be abused or broken such that it is possible to reset the safety valve when the manual knob is in a position other than the "pilot" position. Other prior art fluid control apparatus employ expensive and complex interlocking facilities for preventing the resetting of a safety valve unless a main valve is in a predetermined position.

SUMMARY OF THE INVENTION

The present invention is summarized in that a control apparatus includes a support, rotatable means mounted on the support for operating in response to rotation, depressible means mounted on the support for operating in response to being depressed, a manual dial mounted on the rotatable means for rotating the rotatable means, the dial extending over the depressible means for preventing manual access to the depressible means, and a push button mounted in the dial spaced from the center of rotation of the dial such that when the dial is in a predetermined position the push button is aligned with the depressible means for operating the depressible means.

An object of the invention is to provide a control apparatus which is relatively inexpensive and safe to operate.

Another object of the invention is to assure that a depressible device cannot be operated unless a rotatable device is in a predetermined position.

One advantage of the invention is that abuse or breakage of a depressible button can not allow operation of the button when a rotatable dial is in any position other than a predetermined position.

Additional features of the invention are the provision of facilities, such as spring means or a raised rib, for holding the push button in a raised position; and the provision of an arcuate groove formed in a dial for receiving both a depressible stem and a ridge which holds a push button in a raised position and engages a stop in the groove to limit rotary movement of the dial.

Other objects, advantages and features of the invention will become apparent from the following description of the preferred embodiment taken in conjunction with the drawings.

BRIEF DESCRIPTION OF THE DRAWINGS

FIG. 1 is a perspective view, partially broken away, of a fluid control apparatus in accordance with the invention.

FIG. 2 is a diagram illustrating the functional arrangement of valves in the control device of FIG. 1.

FIG. 3 is a top view of the control device of FIG. 1 illustrating an intermediate or "pilot" position of a dial.

FIG. 4 is a top view of the control device of FIG. 1 illustrating the counter-clockwise or "on" position of a dial.

FIG. 5 is an elevation view in cross section of an alternate control mechanism in accordance with the invention.

DESCRIPTION OF THE PREFERRED EMBODIMENTS

FIG. 1 shows a control apparatus, such as a gaseous fuel control apparatus for a water heater. A housing 12 has an inlet 10 and is connected to a pipe 14 communicating with a pilot burner 15 and to a pipe 18 communicating with a main burner 20. As illustrated in FIG. 2, the housing 12 contains a safety valve 22, a manual valve 32 and a thermostat valve 38 all interconnected in a conventional control arrangement. The safety valve 22 is any suitable valve, such as a magnetic safety valve, for preventing flow of fluid through the manual valve 32 upon the existence of a predetermined condition, such as a decrease in current through a line 24 connected between the magnetic safety valve 22 and a thermocouple 26 sensing a flame of the pilot burner 16. A depressible stem 28 extends through a wall 30 of the housing 12 and is operatively connected with the safety valve 22 for opening the safety valve when the stem 28 is depressed or moved downward. The manual valve 32 is any suitable valve, such as a gas cock valve or a valving arrangement operated by cams, which can be selectively placed in one of a plurality of operating positions 35 by a rotatable shaft 34 extending through the wall 30 of the housing 12 to a dial 36. The operating positions of the manual valve 32 include an "off" position, a "pilot" position for supplying fuel to the pilot burner 16, and an "on" position for supplying fuel to the pilot burner 16 and to a thermostat valve 38 which supplies fuel to the main burner 20. The thermostat valve 38 is any suitable valve which opens when a temperature sensed by a thermostat element 40 drops below a temperature setting of a dial 41 and which closes when the temperature sensed by the element 40 rises above the temperature setting of the dial 41.

The dial 36 has a circular groove 42 formed in the bottom concentric to the axis of rotation thereof into which the end of the stem 28 extends such that the stem 28 is covered by the dial 36 to prevent manual access to the stem 28. The dial 36 has a push button 44 slidably mounted within an opening 46 extending from the groove 42 to the top of the dial 36 with flanges 48 and 50 on the push button 44 extending into an enlarged portion of the groove 42 to limit upward movement of the push button 44 in the dial 36. Arcuate ribs or ridges 52 and 58 extend upwardly from the wall 30 into the groove 42 for engaging a surface of an arcuate slot 54 formed in the bottom of the push button 44 and for holding the push button 44 in a raised position when dial 36 is in a counterclockwise or clockwise position, respectively. A stop 56 is formed in the groove 42 opposite to the push button 44 for engaging the arcuate ribs 52 and 58 and limiting movement of the dial 36.

The stem 28 has a retaining ring 60 for limiting upward movement of the stem 28 and a spring 62 between the bottom of a recess 64 in the wall 30 and a retaining

ring 66 on the stem 28 for urging the stem 28 in an upward direction when not operated by the push button 44.

The ridges 52 and 58 and the stem 28, in its raised position, extend to substantially the same height above the wall 30 to support the push button 44. Suitable provisions such as rounding of the edges of the ridges 52 and 58, the end of the stem 28 and the edges of the push button 44 are made to insure that the push button 44 will easily slide onto the ridges 52 and 58 and the stem without hindering the rotary movement of the dial 36.

In operation of the fluid control apparatus shown in FIGS. 1-4 to reset the safety valve 22 and allow the ignition of the pilot burner 16, the dial 36 is rotated to the "pilot" position, as illustrated in FIG. 3, to position the push button 44 over the stem 28 such that the push button 44 does not engage either of the ridges 52 or 58. The push button 44 is then manually depressed and held in the depressed position to open the safety valve 22 while the pilot burner 16 is ignited and the thermocouple 26 is heated to produce sufficient current in the line 24, to maintain the safety valve 22 in its open or reset position. Release of the push button 44 allows the spring 62 to return the stem 28 and the push button 44 to their raised positions. Then the dial 34 can be rotated to the "on" position illustrated in FIG. 4, to allow the thermostat valve 38 to operate the main burner 20.

When it is desired to have neither the pilot burner nor the main burner 20 operating, the dial 36 is rotated clockwise to the "off" position to terminate the flow of fluid to the pilot burner 16 and the main burner 20. In the event the pilot burner 16 is extinguished by a gust of air, loss of fuel, etc. the thermocouple 26, cools, and the safety valve 22 closes to terminate the fuel flow and prevent the hazardous release of fuel.

When the dial 36 is in a clockwise position, as illustrated in FIG. 1, or the "off" position, the ridge 52 engages the bottom of the push button 44 to maintain the push button 44 in a raised position. The ridge 58 engages the stop 56 to limit the clockwise rotation of the dial 36 to the "off" position. When the dial 36 is in a counterclockwise position or the "on" position, as illustrated in FIG. 4, the ridge 58 engages the bottom of the push button 44 to maintain the push button 44 in its raised position while the ridge 52 engages the stop 56 to limit the counterclockwise rotation of the dial 36 to the "on" position.

FIG. 5 illustrates a second embodiment wherein certain parts are identified by the same numerals which identify parts in FIGS. 1-4 to indicate that those commonly identified parts have similar structure and/or function. A push button 68 is slidably mounted within an opening 70 in a dial 72 mounted on the rotatable shaft 34 extending from the wall 30 of the housing 12. The push button 68 has a compression spring 74 engaging, at one end, an enlarged upper portion of the push button 68 and engaging, at another end, a ledge 76 in the bottom of the opening 70 for normally urging the push button 68 to a raised position where a retaining ring 78 abuts the bottom of the ledge 76. The push button 68 can be used to depress the reset stem 28 only when the dial 72 is in a "pilot" position.

Since many variations, modifications and changes in detail can be made to the present embodiments, it is intended that the above description and the accompany-

ing drawings be interpreted as illustrative and not in a limiting sense.

What is claimed is:

1. A fluid control apparatus comprising
manual valve means for controlling a fluid;
safety valve means for preventing the flow of fluid
through the manual valve means when a predeter-
mined condition exists;
a housing having a wall and means for supporting the
manual valve means and the safety valve means;
a rotatable shaft extending through the wall of the
housing for operating the manual valve means;
a slidable stem extending through the wall of the
housing for resetting the safety valve means, the
stem being spaced from the shaft;
a dial mounted on the shaft and having a shape that
extends over and covers said stem at all times re-
gardless of the rotative position of said dial with re-
spect to the stem so as to prevent manual access to
the stem; and
push button means mounted in the dial and spaced
from the center of rotation of the dial for move-
ment with the dial such that when the dial is in a
predetermined position the push button means is in
a position disposed in alignment with the stem for
operating the stem to reset the safety valve means
upon depression of the push button means.

2. A fluid control apparatus as defined in claim 1
which includes spring means for urging the push button
means to a raised position.

3. A fluid control apparatus as defined in claim 1,
which includes means cooperating with the wall of the
housing for holding the push button means in a raised
position when the dial is in a position rotated from the
predetermined position.

4. A fluid control apparatus as defined in claim 1
wherein the dial has an opening spaced from the center
of rotation of the dial, and wherein the push button
means includes a push button mounted in the opening
of the dial.

5. A fluid control apparatus as defined in claim 4
wherein a spring means is mounted in the opening of
said dial and interposed between said push button and
said dial for urging said push button to a raised position
with respect to said dial, and wherein retaining means
retain said push button in the opening of said dial.

6. A fluid control apparatus comprising
manual valve means for controlling a fluid;
safety valve means for preventing the flow of fluid
through the manual valve means when a predeter-
mined condition exists;
a housing having a wall and means for supporting the
manual valve means and the safety valve means;
a rotatable shaft extending through the wall of the
housing for operating the manual valve means;
a slidable stem extending through the wall of the
housing for resetting the safety valve means, the
stem being spaced from the shaft;
a dial mounted on the shaft and extending over the
stem to prevent manual access to the stem;
a push button mounted in the dial and spaced from
the center of rotation of the dial such that when the
dial is in a predetermined position the push button
is in a position for operating the stem to reset the
safety valve means;
the dial having (a) an arcuate groove in the bottom
thereof concentric with the axis of rotation and (b)

an opening extending from the groove to the top of the dial;
the stem extending into the groove;
the push button extending from the opening in the top of the dial and having a flange in the groove for retaining outward movement of the push button; and
the housing having an arcuately formed ridge extending into the groove for holding the push button in an outward position when the dial is in a position rotated from the predetermined position.

7. A fluid control apparatus as defined in claim 6 wherein

the dial has a stop formed in the groove, and the ridge on the housing cooperates with the stop to limit rotary movement of the dial.

8. A fluid control apparatus comprising manual valve means having at least three operating positions for controlling a fluid;

magnetic safety valve means for preventing the flow of fluid to the manual valve means when a predetermined condition exists;

a housing having a wall for containing the manual valve means and the safety valve means;

a rotatable shaft extending through the wall of the housing and having at least three rotative positions for selecting the operating position of the manual valve means;

a slideable stem extending outward from the wall of the housing for resetting the magnetic safety valve means when the stem is moved inward;

means for normally biasing the stem to an outward position;

a dial mounted on the shaft for rotating the shaft and

extending over the stem to prevent manual access to the stem, the dial having (a) a circular groove in the bottom thereof concentric with the axis of rotation for receiving the outward extending end of the stem, (b) an opening extending from the groove to the top of the dial and (c) a stop formed in the groove opposite the opening;

a push button slidably mounted in the opening of the dial such that when the dial is in an intermediate position the push button is aligned with the stem for operating the stem to reset the magnetic safety valve means, the push button having a flange extending transversely into the groove for limiting outward movement of the push button;

a first arcuate ridge formed on the wall and extending into the groove for holding the push button in an outward position when the dial is rotated clockwise from the intermediate position and for engaging with the stop when the dial is rotated counterclockwise from the intermediate position; and

a second arcuate ridge formed on the wall and extending into the groove for holding the push button in an outward position when the dial is rotated counterclockwise from the intermediate position and for engaging with the stop when the dial is rotated clockwise from the intermediate position.

9. A fluid control apparatus as defined in claim 8 wherein

the stem is spring biased to an outward position; and wherein

the stem, the first arcuate ridge and the second arcuate ridge all extend to substantially the same outward distance from the wall.
